GASEOUS DISCHARGE LIGHTING
APPARATUSEdmund G. Lodge, St. Marys, Pa., assignor to
Stackpole Carbon Company, St. Marys, Pa., a
corporation of Pennsylvania

Application August 3, 1942, Serial No. 453,377

8 Claims. (Cl. 176—124)

This invention relates to electric circuits for gaseous discharge lamps, and more particularly to those in which the lamp is operated from a source of direct current.

A gaseous discharge lamp is one containing a gas that is ionized by a pair of electrically heated filaments. An example of this type of lamp is the tubular fluorescent lamp. One terminal of each filament is connected to a source of alternating current, and the other terminals of the filaments are electrically connected by a normally closed automatic switch, such as a bimetallic switch. When the current is turned on, electricity flows through the filaments and switch until the filaments become hot enough to ionize the gas around them. At about the same time the electrically heated switch snaps open, and the resulting voltage surge, which may reach 800 or 900 volts or even higher, causes ionization of the gas in the tube and reduces the voltage to about 110 volts. An electrical device called a ballast is placed in the circuit to prevent the current from burning out the filaments while the switch is closed.

In many cases it is desirable to use fluorescent lamps and the like where there is no primary source of alternating current, such as in trains and airplanes. It is therefore necessary to make special provision for producing the alternating current necessary to operate the lamps. For this purpose it is common practice to generate alternating current by means of motor generators or dynamotors driven by the available direct current, but they are heavy, bulky, and expensive. In the case of dynamotors their fine and necessarily closely spaced windings often are destroyed when the load is suddenly removed. That is, to keep down the bulk and weight of dynamotors, the wire size and insulation thickness is kept at a minimum, so any unusual surge of voltage caused by an open circuit tends to break through and destroy the insulation. Also, accidental shorts often cause the windings to be burned open due to the small wire size. A multitude of delicate operations are necessary to connect the armature windings to the commutator segments, causing hazards, and requiring close inspection with resulting high cost. All of these disadvantages become particularly objectionable in the case of airplanes, especially those used in warfare where reliability and reduction in weight are highly important. In warplanes the calibrations and needles on indicator dials are coated with fluorescent paints and the lamp tubes are

left uncoated, resulting in the dials glowing while the "black" light from the lamps is invisible.

Vibrators also are used for the purpose of converting low voltage direct current into alternating current so that it can be stepped up by a transformer to a higher voltage. Vibrators have several undesirable features, one of the chief ones being unreliability. The vibration rate of the reed is so limited that fairly large transformers and filters are required. As the reed vibrates, the flow of current removes contact material from one contact and deposits it on the adjoining one. This not only changes the characteristics of the vibrator but it causes the reed to stick. Once sticking begins it is generally necessary to replace the vibrator. Furthermore, vibrators are relatively expensive for their output because they require very careful adjustments to make them operable in the first place.

It is among the objects of this invention to provide gaseous discharge lighting equipment for battery or other direct current operation having means for converting the direct current into alternating current which is compact and relatively light in weight, which is easy and inexpensive to make, which is self-starting, which is highly efficient, and which is sturdy and dependable.

In accordance with this invention the secondary coil of a transformer is connected to the filaments of a gaseous discharge lamp, such as a fluorescent lamp. The primary coil of the transformer has a center tap adapted to be connected to a source of direct current, such as a battery or direct current generator, that is to be converted into alternating current for lighting the lamp. By "center tap" is meant any tap on the primary coil between its end taps and is not to be understood as meaning a tap at the exact center of the winding. A pair of fixed electric contacts are connected to or near the opposite ends of the primary coil for engagement by rotary contact means adapted when rotating to make electrical contact with each of the fixed contacts alternately. The rotary contact means are adapted to be electrically connected to the source of direct current to complete the primary circuit. When the rotary contact means are driven, the flow of direct current to each half of the primary coil is interrupted alternately, and as this current alternately flows in opposite directions in the primary coil, it induces alternating current in the secondary coil connected to the lamp filaments. The transformer steps up the voltage

of the converted current to a point where it is sufficient to operate the lamp.

The means by which the rotary contact means are driven preferably include an armature rotated by electromagnetic means that may consist of the transformer itself or a separate electromagnet. In the former case the armature is journaled in such a position in the transformer that the leakage flux of the transformer rotates the armature. The primary coil of the transformer, or the electromagnetic coil when a separate coil is used, is connected in the circuit in such a manner that as the rotary contact means engage first one fixed contact and then the other, the circuit through the coil is alternately energized and deenergized to produce the periodic magnetic impulses that rotate the armature. The transformer preferably is purposely made to have poor regulation characteristics, such as by winding the secondary with extra fine wire, so that the usual ballast will be unnecessary. With such a transformer the load or resistance of the lamp filaments before the automatic switch opens brings the alternating current voltage down to one proper for filament operation so that the filaments will not burn out. As soon as the switch opens and the gas in the lamp is ionized, the voltage increases to about 110 volts and the lamp operates.

The preferred embodiment of the invention is illustrated in the accompanying drawing in which Fig. 1 is a side view of my current interrupting device by which direct current is converted into alternating current for operating a gaseous discharge lamp; Fig. 2 is a view of the opposite side of the device; Fig. 3 is an end view; Fig. 4 is a plan view; and Fig. 5 is a diagrammatic view of the entire lamp circuit.

Referring to Fig. 5 of the drawing, one terminal of each filament 1 of a gaseous discharge lamp 2, such as a fluorescent lamp, is electrically connected to a normally closed automatic switch 3 which may be a thermo-switch having a bimetallic element that opens the switch when it becomes heated by electric current flowing through it. The other terminals of the filaments are connected by wires 4 to the opposite ends of the secondary coil 5 of a transformer 6. The ends of the primary coil 7 of the transformer are connected by wires 8 to a pair of fixed electric contacts or brushes 9 and 10 that are engaged by a rotating contact member 11. This contact member includes a pair of diametrically opposite live contact segments 12 and 13 which are electrically connected through a collector button 14 and a wire 15 to a source of direct current, such as a storage battery 16. The other side of the battery is connected by a wire 17 to the center tap of primary coil 7. It will be seen that as contact member 11 rotates it connects the battery with first one end and then the other of the primary coil. The current thus flows alternately in opposite directions through the primary and thereby induces alternating current in the secondary coil. The transformer as a whole steps up the voltage of the alternating current to a point satisfactory for operation of the lamp.

For an understanding of the details of construction of the device by which direct current is converted into alternating current for operating the lamp, reference should be made to Figs. 1 to 4. As there shown, the transformer has an E-shape core 20 with a center leg on which is mounted a coil 21 that is a combination of primary and secondary windings 7 and 5, respec-

tively (Fig. 5). Projecting toward each other from the two end legs of the transformer core are core extensions 22 the inner ends of which are spaced apart above the center leg of the core. 5 The metal laminations forming the core are clamped together at the bottom by bolts 23 and at the top by bolts 24.

Mounted on top of core 20 is a cover plate 26 of non-magnetic material, such as brass, which has downturned ears 27 at both ends that overlap the end legs of the core. The lower edge of each ear is notched to permit it to fit over upper bolts 24 and to be clamped by nuts 28 against the core. The central portion of plate 26 is arched over the 15 gap between core extensions 22, and this arched portion projects from both sides of the core where it forms the upper portions of integral substantially cylindrical bearing supports 29.

Attached to the outer end of one of the bearing supports is an insulating plate 31 provided with a pair of outwardly projecting pins 32 on each of which one end of a contact arm 33 is pivotally mounted. The free ends of these arms carry brushes 9 and 10, preferably made from a mixture of powdered silver and graphite, connected by wires 8 to the ends of the primary coil. The two brushes are held by springs (not shown) 25 in engagement with the commutator-like member 11 mounted on the adjacent end of a horizontal metal shaft 34 journaled in bearings 35 mounted in metal bearing supports 29 of cover plate 26.

The commutator includes the pair of electric contact segments 12 and 13 and enough metal segments 36 insulated from them to complete the cylinder without at any time bridging the adjoining brushes. It is preferred to divide the commutator into six segments of equal size embedded in a core 37 of insulating material. The commutator is provided at its inner end with a projecting hub 38 tightly engaging shaft 34 and integral with the live contact segments but separated from segments 36. Engaging this hub is the small collector button 14 carried at the center of a flat spring 39 supported at its ends by metal pins 41 projecting from bearing supports 29. The pins are so positioned relative to the shaft that spring 39 must be bowed slightly so that button 14 makes good contact with hub 38. The contact segments 12 and 13 of the commutator are thus grounded to cover plate 26 and core 20 through button 14, spring 39, and pins 41. As the battery is grounded to core 20 by wire 15, the contact segments are electrically connected to the battery at all times.

It will thus be seen that, as the commutator revolves, its live segments engage first one brush and then the other. This causes the current from battery 16 to pass alternately through each brush so that it flows through the primary coil first in one direction and then the other to give an alternating current effect. Also, due to the break in the circuit every time a live segment of the commutator leaves a brush and before the other brush is engaged by a live segment, the transformer is alternately energized and deenergized.

The commutator is rotated by means of an armature 45 rigidly mounted on the central portion of shaft 34. The armature has a plurality of radial projections or wings, preferably four, spaced at intervals over 90° where two live commutator contacts are used. When either one of the two primary contact segments is in engagement with one of the brushes 9 and 10, current flows through the transformer and produces a leakage flux in the gap between the core exten-

sions 22. This leakage flux or magnetic impulse attracts the adjacent projection of the armature and draws it toward it, thereby rotating the armature. This moves the live contact of the commutator out of engagement with the adjoining brush and breaks the circuit through the transformer. However, the momentum of the rotating armature carries the other live contact segment into engagement with the other brush so that the transformer is again energized and another impulse thus given to the armature. In this manner the armature is rotated at high speed.

Referring more specifically to Fig. 1, the rotor, which consists of the armature, commutator and supporting shaft, is shown in one of the four similar positions it should be in for starting and for rotation in a clockwise direction. The lower right-hand projection of the armature is closer to the center leg of the transformer core than is any other part of the armature, and contact segment 12 is in contact with upper brush 10 but about to leave it. When the current from battery 16 is turned on, the transformer is energized and the lower right-hand projection of the armature drawn around toward the center leg of the transformer due to the effort of the flux set up in the transformer to close the gap between its center leg and the armature or to find the path of least resistance. By the time the armature projection points within about 2° of straight down so as to afford a low resistance path for the flux, contact segment 12 has left brush 10 so that the transformer is deenergized, but momentum continues the rotation of the armature until contact segment 13 makes contact with brush 9 so that the transformer is again energized and the cycle repeated. Shortly after segment 13 leaves brush 9 it moves across brush 10, after which contact 12 engages brush 9, whereby the armature is continuously rotated at high speed.

In order that the rotor will always be self-starting, means is provided for stopping the armature with one of its projections in the position shown in Figs. 1 and 2 whenever the current to the device is turned off. For this purpose, as shown in Fig. 2, a hollow cylinder 41, mounted on the side of the transformer opposite to that from which the commutator member projects, contains a solenoid coil 48 that is connected in series in wire 17 between the battery and a filter condenser 49 connected to that wire and grounded to the transformer core. A fixed core 49 is disposed in the lower half of the solenoid inside of a tube 50 that projects above the coil. This tube guides a vertically reciprocable movable core 51 that extends above cylinder 41 and that is urged upwardly by an encircling spring 52 compressed between the top of the tube and the bottom of a disc 53 rigidly mounted on the upper portion of the movable core. The upper end of the movable core is bifurcated and receives the slotted outer end of an arm 54 the inner end of which is pivoted to the lower portion of a bearing support 28. The arm and core are pivotally connected by a pin 55. The arm is provided near its inner end with an upwardly extending integral projection 56 from the upper end of which a roller 57 projects outwardly. This roller is adapted to engage the edge of a disc-like cam 58 rigidly mounted on the projecting end of rotor shaft 34. The cam is more or less square with a central depression in each edge, and it is so positioned relative to the armature that when roller 57 engages the cam in any one of its four depre-

sions the armature is in starting position, which is shown in Figs. 1 and 2.

When the current is turned off, the spring 52 lifts movable core 51 and thereby swings arm 54 upwardly to press roller 57 against the edge of the cam. The rotating cam comes to rest with the roller disposed in one of its four depressions, and the armature thus is in starting position. As soon as the current is turned on again the magnetic pull on the armature is sufficient to cause a high part of the cam to force roller 57 outwardly. This action swings the outer end of the arm down and thereby forces the movable core down into the solenoid far enough to bring it into the field of magnetic attraction of the fixed core 49. The latter continues to draw the movable core downwardly and the roller is thus entirely freed from the cam so that the rotor is free to rotate. Lever 54 then is in the dotted-line position shown in Fig. 2.

Another feature of this invention is that the transformer is preferably wound to provide poor electrical regulation. This may be done by winding the secondary coil with extra fine wire. The regulation is most suitably such that when the current is first turned on the voltage of the secondary coil can be held down to about 20 volts by the electrical resistance of the lamp filaments. With this voltage there is no danger of burning out the filaments. As soon as the automatic switch opens there is a surge in voltage up as high as 900 volts or higher. This causes ionization of the gas in the lamp tube, after which the current drawn is such that the voltage output of the transformer is raised and stabilized at about 110 volts A. C. With this type of transformer it is not necessary to use a ballast and therefore the cost and weight of such an element are eliminated.

40 Gaseous discharge lighting equipment constructed in accordance with this invention makes use of a current converting device that is neither bulky nor heavy for its output. The device is inexpensive to make and is dependable in operation. Unlike a dynamotor in which the armature 45 windings have to be soldered to many segments of a commutator, the only connections here are to the opposite ends of the two transformer coils and to the center tap of the primary coil. The 50 use of a transformer permits layer winding and layer insulation, which are the easiest, without thought of bulk and weight.

According to the provisions of the patent statutes, I have explained the principle and operation of my invention and have illustrated and described what I now consider to represent its best embodiment. However, I desire to have it understood that, within the scope of the appended claims, the invention may be practiced otherwise than as specifically illustrated and described.

I claim:

1. The combination with a gaseous discharge lamp provided with spaced filaments, of a transformer having its secondary coil connected to said filaments, the primary coil of the transformer having a center tap adapted to be connected to a source of direct current that is to be converted into alternating current, a pair of fixed electric contacts connected to the opposite ends of the primary coil, rotary contact means for connection to said source of direct current and adapted when rotating to make electrical contact with each of said fixed contacts alternately with a break between, a rotatable armature operatively

connected to said rotary contact means for driving said means to interrupt the flow of direct current to each half of said primary coil alternately whereby said secondary coil supplies alternating current to said lamp filaments, and means for stopping said rotary contact means in electrical contact with one of said fixed contacts when the direct current to the primary coil is shut off to thereby assure self-starting of the armature when said current is turned on again.

2. The combination with a gaseous discharge lamp provided with spaced filaments, of a transformer having its secondary coil connected to said filaments, the primary coil of the transformer having a center tap adapted to be connected to a source of direct current that is to be converted into alternating current, a pair of fixed electric contacts connected to the opposite ends of the primary coil, rotary contact means for connection to said source of direct current and adapted when rotating to make electrical contact with each of said fixed contacts alternately with a break between, a rotatable armature operatively connected to said rotary contact means for driving said means to interrupt the flow of direct current to each half of said primary coil alternately whereby said secondary coil supplies alternating current to said lamp filaments, means for stopping said rotary contact means in electrical contact with one of said fixed contacts when the direct current to the primary coil is turned off, and means for automatically moving said stopping means out of operative position when said direct current is turned on again.

3. The combination with a gaseous discharge lamp provided with spaced filaments, of a transformer having its secondary coil connected to said filaments, the primary coil of the transformer having a center tap adapted to be connected to a source of direct current that is to be converted into alternating current, a pair of fixed electric contacts connected to the opposite ends of the primary coil, rotary contact means for connection to said source of direct current and adapted when rotating to make electrical contact with each of said fixed contacts alternately with a break between, a rotatable armature operatively connected to said rotary contact means for driving said means to interrupt the flow of direct current to each half of said coil alternately whereby said secondary coil supplies alternating current to said lamp filaments, a stop member mounted for automatically stopping said armature in a predetermined position when the direct current is turned off, and electromagnetic means for moving said stop member out of stopping position when said primary coil is energized.

4. The combination with a gaseous discharge lamp provided with spaced filaments, of a transformer having its secondary coil connected to said filaments, the primary coil of the transformer having a center tap adapted to be connected to a source of direct current that is to be converted into alternating current, a pair of fixed electric contacts connected to the opposite ends of the primary coil, rotary contact means for connection to said source of direct current and adapted when rotating to make electrical contact with each of said fixed contacts alternately with a break between whereby the circuit through the primary is periodically deenergized and the current in said circuit flows through first one of said contacts and then the other to induce alternating current in said secondary, a rotatable armature having a plurality of radial projections

adapted to be successively attracted by periodic magnetic impulses of said transformer, means connecting the rotary contact means to said armature for rotation thereby, a cam connected to said armature for rotation thereby, spring-biased means for engaging said cam when the direct current is turned off whereby to stop said armature with one of its projections adjacent said transformer and with said rotary contact means in engagement with one of said fixed contacts, and electromagnetic means for withdrawing said spring-biased means from said cam when said primary coil is energized.

5. The combination with a gaseous discharge lamp provided with spaced filaments, of a transformer having its secondary coil connected to said filaments, the primary coil of the transformer having a center tap adapted to be connected to a source of direct current that is to be converted into alternating current, a core for said coils having two ends facing each other, a pair of fixed electric contacts connected to the opposite ends of the primary coil, rotary contact means for connection to said source of direct current and adapted when rotating to make electrical contact with each of said fixed contacts alternately with a break between, and an armature rotatably mounted between said core ends and adapted to be rotated by the periodical magnetic attraction of the core, said armature being operatively connected to said rotary contact means for driving the latter whereby to interrupt the flow of direct current to each half of said primary coil alternately and to alternately energize and deenergize that coil.

6. The combination with a gaseous discharge lamp provided with spaced filaments, of a transformer having its secondary coil connected to said filaments, the primary coil of the transformer having a center tap adapted to be connected to a source of direct current that is to be converted into alternating current, a magnetic core extending through said coils, a pair of fixed electric contacts connected to the opposite ends of the primary coil, rotary contact means adapted to be electrically connected to said source of direct current and adapted when rotating to make electrical contact with each of said fixed contacts alternately, and a rotatable armature mounted adjacent said core and having a plurality of radial projections adapted to be successively attracted by periodic magnetic impulses of the core, said armature being operatively connected to said rotary contact means for rotation thereof whereby to interrupt the flow of direct current to each half of said primary coil alternately and to alternately energize and deenergize that coil.

7. The combination with a gaseous discharge lamp provided with spaced filaments, of a transformer including concentric primary and secondary coils, the secondary coil being connected to said filaments and the primary coil of the transformer having a center tap adapted to be connected to a source of direct current that is to be converted into alternating current, a magnetic core common to both coils, a pair of fixed electric contacts connected to the opposite ends of the primary coil, a rotatable shaft, an armature rigidly mounted on said shaft and adapted to be rotated by periodic magnetic attraction of said core, and a commutator-like contact member rigidly mounted on one end of said shaft and adapted to be connected to said source of direct current, said contact member being adapted when rotating to make electrical contact al-

ternately with each of the fixed contacts connected to the primary coil, whereby to interrupt the flow of direct current to each half of the primary coil alternately and to alternately energize and deenergize that coil.

8. The combination with a gaseous discharge lamp provided with spaced filaments, of an automatic switch electrically connecting the filaments and adapted to open when said filaments reach a predetermined temperature to strike an arc between the filaments, a transformer having its secondary coil connected to said filaments, the primary coil of the transformer having a center tap adapted to be connected to a source of direct current that is to be converted into alternating current, a pair of fixed electric contacts con-

10 nected to the opposite ends of the primary coil, rotary contact means for connection to said source of direct current and adapted when rotating to make electrical contact with each of said fixed contacts alternately, and means for driving said rotary contact means to interrupt the flow of direct current to each half of said primary coil alternately whereby said secondary coil supplies alternating current to said lamp filaments, said transformer having poor regulation characteristics to thereby cause the electrical resistance of the filaments before said switch opens to reduce the voltage of said alternating current to a point at which it will not burn out the filaments.

15 EDMUND G. LODGE.
